UNITED STATES PATENT OFFICE.

JOHN F. LEICHT, OF SHELBY, MICHIGAN.

EXTENSION STEPLADDER.

Application filed March 14, 1924. Serial No. 699,248.

To all whom it may concern:

Be it known that I, JOHN F. LEICHT, a citizen of the United States, residing at Shelby, in the county of Oceana and State of Michigan, have invented certain new and useful Improvements in Extension Stepladders, of which the following is a specification.

The present invention relates to a combined step and extension ladder and is primarily intended to be used by gardeners in trimming fruit trees or collecting fruit and tending to the trees in general.

The main object of the invention is to provide a ladder of this character which can be folded midway between its two ends thus providing a stepladder, the free end of the extension portion of the ladder resting on the ground.

Another object of the invention is to provide a ladder that can be extended by swinging adjustment of its extension portion and by firmly locking the extension and base portions together.

When in extended position the side rails of the extension portion form straight continuations of the side rails of the base portion and the arrangement is such that the lower ends of the base portion of the ladder are spread well apart while the upper end of the ladder is tapered to a point.

In the accompanying drawing,—

Figure 1 is a perspective view of the ladder adjusted for use as a stepladder;

Figure 2 is a side elevation of the ladder in an extended position leaning against the trunk of a tree;

Figure 3 is a fragmentary front elevation of the middle portion of the ladder;

Figure 4 is a fragmentary vertical section showing the means for locking the sections in extended relation, and

Figure 5 is a front elevation of the ladder extended and shown on a smaller scale.

In the drawing, reference numeral 10 indicates the base section of the ladder and 11 the extension section thereof. The base section 10 has two side rails 12 which are inclined upwardly with relation to each other so that their lower ends 13 are further apart than their upper ends 14. Between these side rails are supported a plurality of steps or rungs 15 firmly secured in the side rails in the usual manner.

At the lower end of the base section 10 are two side braces 16, the upper ends of

which are secured as at 17 to the rails 12 a short distance above the lower ends 13 thereof. These braces are disposed at an acute angle to the side rails 12, as best seen in Fig. 1, and are held in such position by spacing blocks 18 and a tension rod 19 which is secured through the side rails 12 and the braces 16. The lower ends of the braces 16 are slightly raised above the ends 13 of the side rails 12 for the purpose of permitting said ends 13 to firmly engage in the ground to prevent any displacement of the side rails. In this manner when the ends 13 of the side rails 12 have penetrated deep enough into the ground the lower ends 20 of the braces will also engage the ground.

The extension section 11 of the ladder consists of two side rails 21 united by steps or rungs 22 in the same manner as already described with regard to the base section 10 of the stepladder. The side rails 21 have preferably the same inclination with relation to each other as the side rails 12 of the base section of the ladder so that when the ladder is extended, the side rails of the extension section form straight continuations of the side rails 12 of the base section, as best seen in Fig. 5.

Between the outer ends of the side rails 21 is inserted a filling piece 23 which is bolted or riveted to the side rails 21, as best seen in Fig. 1. This filling piece 23 projects a short distance beyond the ends of the side rails 21 in order to form a spur or toe 24 adapted to penetrate into the ground when the step-ladder is used, as seen in Fig. 1.

The inner ends 25 of the rails of the extension section of the ladder are connected with the corresponding ends of the rails 12 by means of hinges 26 secured to the rails in such a manner that when the extension section 11 is swung upwardly the flat ends 14 of the side rails 12, of the section 10, will form abutments for the similarly shaped ends 25 of the side rails 12 of the extension section of the ladder. In this manner when the ladder is erected, as seen in Fig. 2, leaning against a tree, a rigid connection will be formed between the extension section and base section of the ladder. In order to prevent the ladder from collapsing when moved from one tree to another and to render the connection between the sections still more rigid, a yoke 27 is provided at the hinged end of the extension section 11. This yoke preferably comprises two flat straps 28 which are

5 bolted or riveted on the front faces of the respective side rails 21 and project a sufficient distance beyond the ends 25, of the rails of the extension section 11, to overlap the front faces of the ends 14 of the rails of the base section of the ladder.

In order that the straps 28 may be locked in overlapping engagement with the rails 12, the straps 28 are formed with longitudinal slots 29 to accommodate locking members 30 mounted upon the upper ends 14 of the side rails 12. These members are preferably L-shaped, as best seen in Fig. 4, and the laterally turned end 31 of each member is adapted to engage through the slot 29 in the corresponding strap 28 and then be turned, as shown in Figs. 2 and 3, to engage against the outer side of the corresponding strap 28. Nuts 32 and washers 40 are fitted upon the 20 ends of the shanks of the members 30 and abut against the rear faces of the side rails 12 and when the members 30 are turned so that their angularly projecting locking portions 31 extend upwardly, these portions of the locking members may readily engage 25 through the slots 29 when the extensions are moved about their hinges 26 to assume an aligned relation, the rotative adjustment of the said members 30 to position with their 30 locking portions 31 projecting downwardly, serving to bring these portions into engagement with the outer sides of the respective strap extensions at the lower ends of the slots 29. The free ends of the straps 28 are 35 connected by means of a reinforcing strap 33

which is riveted to the straps 28, and has its ends 27 bent at right-angles, as at 37, to engage the sides of the side rails 12.

When the base and extension sections of the ladder are locked together in this manner 40 the ladder can be employed as an ordinary ladder and has the advantage over ordinary ladders, that its base is increased in width by the spread out braces 16. By the engagement of the ends 13 of the side rails 12 in the 45 ground slipping of the ladder is prevented. Furthermore, when used as a stepladder the spur 24 will also enter the ground and prevent slipping of the extension section of the ladder away from the base section. 50

Having thus described the invention, what is claimed as new is:

An extension ladder comprising complementary sections hingedly connected, each section including side rails, locking members 55 rotatably mounted upon the rails of one section a short distance from the hinged joint, longitudinal strips secured to the rails of the other section and projecting to overlap the hinge joint and engage the rails of the section carrying the locking members and slotted to receive the latter, and a transverse strip connecting the slotted ends of the longitudinal strips and having their outer ends bent laterally to embrace the outer sides of 60 the rails carrying the locking members when the ladder is extended. 65

In testimony whereof I affix my signature.

JOHN F. LEICHT. [L. S.]
